RESEATING TOOL

Hosea David Waters, Stillwater, Okla.

Application April 19, 1939, Serial No. 268,839

2 Claims. (Cl. 90—12.5)

This invention aims to provide a simple but effective means for refinishing the seat of a faucet, novel means being provided for securing rotation of the tool, and the construction being such that the tool may be turned end-for-end, and parts of it interchanged, to accommodate the device to the faucet that is being reseated.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawing:

Fig. 1 shows in elevation, a tool constructed in accordance with the invention, in place for use;

Fig. 2 is a section wherein parts remain in elevation.

The device forming the subject matter of this application is adapted to be employed for refinishing the seat 1 of a faucet 2.

The tool comprises an elongated cylindrical body 3, including spindles 4 and 5, of different diameters.

The spindles 4 and 5 are provided at their outer ends with retainers 6.

A first rotator 7 is detachably assembled with one retainer 6, and a refinishing tool 8 is detachably assembled with the other retainer 6.

A second rotator 9 is mounted on the intermediate portion of the body 3, and supplements the first rotator 7 in obtaining a proper rotation of the tool, and proper pressure cooperation between the tool 8 and the seat 1.

The body 3 is reversible, end-for-end, whereby the appropriate spindle 4 or 5 may be caused

to fit closely, and for rotation, in the opening 10 of a faucet cap 11.

The retainers 6 are of duplicate construction, whereby the first rotator 7 and the refinishing tool 8 may be interchanged on the retainers 6, 5 when the body 3 is reversed end-for-end.

The device is further characterized by the fact that the spindles 4 and 5 define a shoulder 12, forming an abutment for the second retainer 9. The retainer 9 may be held in place by a cross pin 14, or otherwise.

Specifically, the retainers 6 may be reduced, threaded tips, defining shoulders 15 against which the first rotator 7 and the tool 8 abut.

The rotators 7 and 9 may be hand wheels, as depicted in the drawing. The tool 8 may be of any desired construction, and one tool may be replaced by another, as the nature of the work may demand.

The device is simple in construction, but will be found thoroughly advantageous for the ends in view.

What is claimed is:

1. In a device for refinishing the seat of a faucet, a body comprising spindles of different diameters, the spindles being provided at their outer ends with retainers, a first rotator detachably assembled with one retainer, a refinishing tool detachably assembled with the other retainer, and a second rotator mounted on the intermediate portion of the body, the body being reversible, end-for-end, whereby the appropriate spindle may be caused to fit closely, and for rotation, in the opening of a faucet cap, the retainers being of duplicate construction, whereby the first rotator and the refinishing tool may be interchanged on the retainers, when the body is reversed end-for-end.

2. A device for refinishing the seat of a faucet, constructed as set forth in claim 1, and further characterized by the fact that the spindles define a shoulder, forming an abutment for the second rotator.

HOSEA DAVID WATERS.
